UNITED STATES PATENT OFFICE.

JOHN M. WADDELL, DECEASED, LATE OF GREENFIELD, OHIO, BY DEAN T. WADDELL,
EXECUTOR, OF GREENFIELD, OHIO.

LEVER-ACTUATING MECHANISM.

Original application filed April 13, 1922, Serial No. 552,112. Divided and this application filed July 10,
1924. Serial No. 725,291.

This invention relates to lever mechanisms such as may be employed in raising the covers of display cases and in various other ways.

5 An object of the invention is to provide a lever mechanism that is simple and efficient in construction and operation.

Another object is to provide a device of this kind, which may be easily operated 10 from one source and which is practically locked against movement from any other source.

Another object is to provide a device of this character which requires a minimum of 15 effort to operate.

These and other objects are attained by the means described herein and disclosed in the accompanying drawings, in which:

Fig. 1 is a rear elevational view of a display case having embodied therein a lever mechanism of the invention.

Fig. 2 is a cross sectional view on line 2—2 of Fig. 1 showing the lever mechanism.

Fig. 3 is an enlarged fragmental detail 25 of the operating means for the lever mechanism of my invention.

In order to set forth the lever mechanism of the invention in a practical and operative form, it will be described as being embodied 30 in a display case such as is set forth in the co-pending application, Serial No. 552,112, filed April 13, 1922, and of which application this is a divisional application.

A display case 9 which may comprise a 35 base or lower section 10 upon which is mounted an upper case 11 consisting of a glass panel through which the goods displayed therein may be seen. The frame of the case is made by any suitable material such as lumber or steel, and the construction 40 may be that usually employed for making cases of this type. The case may have sides 12 and 13 between which suitable panels such as 14 and 15 may extend, thereby providing a front and back for the case. A front bar or rail 16 extends between the sides 12 and 13 and has formed on it a ledge 17 upon which the forward end of a top 18 may engage. The front portion of a case 45 would be preferably provided with a glass panel 19. The rear end of the top 18 is hingedly mounted upon a cross bar 20 extending between the ends. The top 18 is so mounted that the said forward end, which normally lies upon the ledge 17, may

be swung upwardly about the pivotal mounting 21 of said top. When the top or lid 18 is in its normal position, it is inclined downwardly from the bar 20 to the rail 16, and the engagement of the lower edge of 60 said end of the top on the rail together with the engagement of the ends of the top upon the sides 12 and 13 of the case, effects a closure for a display chamber 210. The top may be provided with a glass panel 22. Wares to be displayed, may be placed within the chamber 22, either upon shelving or in containers secured to cross bars 23 extending longitudinally of the case. In so far as relates to this invention, the exact structure 70 of the case and the manner of displaying the wares therein, would be governed solely by choice.

The lever mechanism of the invention is adapted to raise and lower the lid 18, and may be accomplished only by an attendant who would stand at the rear of the case. The lid 18 is actuated about its pivotal mounting by means of a handle 38, the opposite ends of which are mounted upon bars 39, secured by means of pivots 40 upon rods 41, which rods are pivotally mounted intermediate their ends, upon the sides of the case. The pivotal mounting of the rods 41 is preferably effected by means of brackets 42 mounted upon the ends of the case, and carrying pivots 43 supporting the rods 41. The brackets 42 are disposed within the chamber 210, and the rods 41 extend through slots 44 in the rear of the case. The handle and bars 39 are disposed at the rear of the case and exteriorly thereto. The outer end of the rod 41 carries a pin 45 which extends into and in large perforation 46 in the bar 39. This arrangement is resorted to solely 90 to limit the extent to which the bar 39 may move about its pivot 40. A second pin 47 mounted on the outer end of the rod 41 is disposed in such position that normally when the parts are in their normal position as shown in Fig. 2, the pin 47 is disposed above the upper end of a spring 48. The lower end of the bar 39 has a round nose 49 formed on it, which engages the upper and free end of the spring 48. The parts bear such relation that when the handle is moved or pressed downwardly to the position shown in dotted lines in Fig. 2, the nose 49 on the bar will move the upper end of the spring 48 from below the pin 47. This ar- 100 105 110

arrangement of parts is in effect a lock precluding locking of the top 18, by any other means than the handle 38. A spring 50 has one of its ends secured upon the frame of the casing, and has its other end upon the rod 41 intermediate the pivotal mounting 43 of the exterior end of said rod. A link 51 has its lower end pivotally mounted upon the inner end of the rod 41, and has its upper end pivotally mounted upon a suitable pivot 52, carried by the bracket 53, which bracket is mounted on the inner or lower surface of the lid 18. Referring to Fig. 2, and in view of the foregoing explanation, it will be apparent that by exerting a downward pressure upon the handle 38, so as to cause the handle 38 to assume the position shown in dotted lines, the spring 38 is moved below the spring 47 whereby the outer end of the rod 41 may be moved downwardly. This movement of the rod is about the pivotal mounting 43, wherefore the upward movement of the inner end of the rod 41 is transmitted through the link 51 to the lid 18, thereby actuating the lid about its pivotal mounting 21, and thus raising the same to the position shown in part in dotted lines. When the handle is released, the weight of the lid 18, causes the lid to move to its closed position, against the action of the spring 50. The resistance of the spring 50 to the lowering of the lid 18 is augmented by the tendency of the lid in its downward movement to compress the atmosphere in the chamber 210, this serving to cushion the engagement of the lid upon the rail 16.

In order to be able to lock the lid in its lower position, there is provided an arm 54 which is pivotally mounted intermediate its ends on a suitable mounting or pivot 55 mounted on the end of the case. The upper end of the arm is notched, whereby a finger 56 is formed, the finger being adapted to engage a catch 57 mounted upon the inner switch of the lid 18. An arm such as 54 is mounted at each end of a compartment, and extends into the lower section 10, where the ends of said arms are mounted upon a bar 60. A lock 61 mounted on the lower side of the bar 60 is pivotally connected to the forward end of a rod 62, the rear end of which rod is disposed adjacent the back of the lower portion of the casing. A spring 63 has one of its ends mounted upon the casing, and its other end hooked to a perforation 64 near the end of the rod 62. A suitable bolt mechanism 66 may be supplied upon the inner wall of the casing and is adapted to retain the rod 62 in a forwardly extended position, in which position the top 18 is locked by means of the finger 56 and hook 57, or it may cause the rod 62 to assume the position shown in dotted lines in Fig. 2 in which the finger 56 is free from engagement with the hook 57. Suitable doors such as

65, 67 and 68 in the rear of the case provide access to the locking mechanism 66. Thus, when the finger 56 is in the position shown in solid lines in Fig. 2, and the doors 65, 67 and 68 are locked, the entire case is sealed against unauthorized opening. The operation is as follows:

The locking of the lever mechanism against all movement having just been described, need not be repeated. The lid 18 may be moved about its pivotal mounting 21 by pressing downwardly upon the handle 38. The nose 49 engages the spring 48 and moves said spring to a position shown in dotted lines in Fig. 2. The movement of the handle about its pivot 40 is limited by the engagement of the pin 45 upon the wall of the perforation 46, diametrically opposed from that which said pin engages as shown in Fig. 2. At this time, the bar 49 also engages the spring 47, wherefore the continued downward pressure upon the handle 38 carries the outer end of the rod 41 downwardly about the pivotal mounting 43, thereby releasing the spring 50 of part of the strain to which it is subjected, and at the same time lifting the lid 18 by means of the link 51. When the lid 18 is to be lowered, the rod 41 and bar 39 are permitted to resume their normal positions. When the handle 38 is released, the spring 48 riding against the nose 49 moves the bar 39 to the position shown in Fig. 2, and the upper end of the spring 48 assumes a position below the pin 47, thereby precluding the lifting of the lid 18 from the front or side of the case. A pin 70 is employed to limit the movement of the arm 54.

What I claim is:

1. In a lever actuating and controlling mechanism, the combination of a pivotally mounted lever, a perforated bar pivotally mounted on the end of the lever, a pair of pins on the lever, one pin extending into the perforation in the bar, the other pin laying in the path of the bar about its pivotal mounting, the pivotal mountings and the pins bearing a relation such that both pins may engage the bar at the same time, a spring adapted to lie normally in the path of the second mentioned pin and to preclude movement of the lever about its pivotal mounting, and a nose on the bar for engaging the spring, and moving the spring out of the path of the second mentioned pin prior to the engagement of the bar upon the second mentioned pin.

2. In a lever actuating and controlling mechanism, the combination of a pivotally mounted lever, a perforated bar pivotally mounted on one end of the lever, a pair of pins on the lever, one pin extending into the perforation in the bar, the other pin laying in the path of the bar about its pivotal mounting, the pivotal mountings and the pins bearing a relation such that both pins

may engage the bar at the same time, a spring, a lug on the spring adapted to lie normally in the path of the second mentioned pin, and to preclude movement of the lever 5 about its pivotal mounting, and a nose on the bar for engaging the spring, and moving said spring and the lug out of the path of the second mentioned pin prior to the engagement of the bar upon the second mentioned pin.

3. In a device of the class described the combination of a pivotally mounted lever, a movable abutment normally locking the lever against movement and a control bar 15 pivotally mounted on the lever and having limited pivotal movement on said lever for abutting and removing the movable abutment from the path of the lever, further movement of the bar serving to move the 20 lever and bar as a unit about the pivotal mounting of the lever.

4. In a device of the class described the combination of a pivotally mounted lever, a pin on the lever, locking means normally 25 disposed in the path of the pin, and a bar

pivotsly mounted on the lever and adapted for limited pivotal movement thereon for removing the locking means from the path of the pin, further movement of the bar serving to bring said bar into abutment with the 30 pin and causing the bar to effect movement with the lever.

5. In a lever actuating and control mechanism the combination of a pivotally mounted lever, a pin on the lever, a locking means 35 normally disposed in the path of the pin and precluding movement of the lever, and an actuating bar pivotally mounted intermediate its ends on the lever and adapted for initial independent pivotal movement to remove the locking means in the path of the pin whereby the bar may abut the pin to transmit further movement of the bar to the lever.

In testimony whereof, I have hereunto 40 subscribed my name this 7th day of July, 1924.

DEAN T. WADDELL,
